UNITED STATES PATENT OFFICE.

ERNST DAIBER AND PAUL A. BITTER, OF KIEL, GERMANY.

WORKING CYLINDER FOR INTERNAL-COMBUSTION ENGINES.

1,159,832.

Specification of Letters Patent.

Patented Nov. 9, 1915.

Application filed July 3, 1914. Serial No. 848,883.

To all whom it may concern:

Be it known that we, ERNST DAIBER and PAUL A. RITTER, citizens of the German Empire, residing at Kiel, Germany, have invented certain new and useful Improvements in Working Cylinders for Internal-Combustion Engines, of which the following is a specification.

The subject matter of the present invention resides in a further development of the working cylinder for internal combustion engines described in the copending application Serial No. 808,590, filed December 24, 1913. The combustion chamber in said application is inclosed by a hood-shaped cover, which may expand freely both in axial and radial direction.

The object of the present invention is now to construct this cover so that the walls inclosing the combustion chamber may be effectively cooled.

Two embodiments of the invention are illustrated in the accompanying drawing, where:

Figure 1 shows an axial section of the upper portion of an upright internal combustion engine and Fig. 2, a similar view of a modified form of the present invention.

The embodiment represented in Fig. 1 will first be described. The interchangeable, hood-shaped cover B, is, according to the present invention constructed with double walls, the wall b¹ which comes in direct contact with the combustion gases having less thickness than the outer wall b². The necessary stiffness of the inner wall is therefore assured by ribs b³, which are arranged between the walls b¹ and b². The wall b² and the ribs b³ are provided with apertures for the cooling water. By means of the now described formation of the hood-shaped cover B of the copending application, a very effective cooling is brought about of the wall inclosing the combustion chamber, because both the thin inner wall b¹ and the stronger outer wall b², being flushed on both sides by cooling water, provide good means for leading off heat.

The embodiment represented in Fig. 2 differs from that in Fig. 1 therein, that the cover B is here made in two parts, the thin wall b¹ on the one hand, and the stronger wall b², which serves as bearing, on the other hand, each form a unit by itself. This has

the advantage that the manufacture of the cover is greatly simplified. The ribs b³ are in this case integral with the wall b².

We claim:

1. In a cylinder for internal combustion engines having a closed surrounding jacket with an integral head and a liner therein, an interchangeable double-walled cap-shaped cover removably attached to the liner and surrounding the combustion chamber, the inner wall of said cover, coming in direct contact with the combustion gases, being made very thin and the outer wall made comparatively thick, ribs extending in the direction between the two walls supporting the inner wall and creating a plurality of spaces for cooling fluid.

2. In a cylinder for internal combustion engines having a closed surrounding jacket with an integral head and a liner therein, an interchangeable double-walled cap-shaped cover removably attached to the liner and surrounding the combustion chamber, the inner wall of said cover, coming in direct contact with the combustion gases, being made very thin and the outer wall made comparatively thick, ribs extending in the direction between the two walls supporting the inner wall and creating a plurality of spaces for cooling fluid, said spaces having intercommunication.

3. In a cylinder for internal combustion engines having a closed surrounding jacket with an integral head and a liner therein, an interchangeable double-walled cap-shaped cover removably attached to the liner and surrounding the combustion chamber, the inner wall of said cover, coming in direct contact with the combustion gases, being made very thin and the outer wall made comparatively thick, ribs extending in the direction between the two walls supporting the inner wall and creating a plurality of spaces for cooling fluid, said spaces having intercommunication, each of said walls forming a unit.

In testimony whereof the foregoing specification is signed in the presence of two witnesses.

ERNST DAIBER.
PAUL A. RITTER.
